SLIDING COMB

Werner Griesel, Hamburg, Germany, assignor to
 Johannes Plön, Hamburg-Wilhelmsburg, Germany

Application June 2, 1937, Serial No. 146,031

4 Claims. (Cl. 132—15)

The present invention relates to those sliding combs (Schiebekämme) which can be made to emerge from a sheath by the sideward motion of a slide fitted with obliquely arranged slots, in a direction which is at right angles to that followed by said motion. Up to now this arrangement has been subject to a considerable disadvantage inasmuch as the slide referred to had to be comparatively long so as to provide space for the but slightly inclined slots. This, again, made it necessary to make the comb disproportionately long; because, if the obliquity of the slots were to be increased, two drawbacks would result. First, the components of force directed upward in a vertical direction that would arise from the sideward motion of such highly oblique slots would cause the sheath to leave the strap surrounding it. Second, the comb itself would be subject to a tilting movement, and consequently it would be jammed in the sheath.

The invention prevents these drawbacks by arranging the strap surrounding the sheath in such a manner that it is made impossible for the sheath to leave the strap even though the guide slots are highly oblique, so that the slide—and therefore the comb itself—need not be long.

Fig. 1 is a view of the blank from which the cover is made.

Fig. 2 is a sectional view showing the comb and cover.

This object is attained by the following constructional device. As shown by Fig. 1, a piece of material—e. g., a piece of sheet metal (1)—is provided with a perforation (2) in its middle part. Above this perforation, the piece of sheet metal has two flanges (3) and (4) projecting on either side as well as a projecting flange (5) on the upper longitudinal edge. By bending the piece (1) around the perforation edge (6), the flanges (3), (4) and (5) are bent at right angles, so that on both sides of the comb the face walls (3') and (4') are formed, whilst a longitudinal edge (5') is formed on top. A strap (7) surrounding all these parts is then placed around the piece of sheet metal thus bent that the lower ends (8) and (9) of the strap are bent around the face walls (3') and (4'). By introducing the comb (10) into the sheath thus formed, a slide (11) can be used whose guide slots (12) are arranged in a highly oblique manner, because the component of power with which we are now concerned is no longer able to force the strap (7) upward and to make it leave the sheath. Pins fitted to the comb (10) are guided

In order to prevent a tilting movement of the comb in the sheath, a second grate (14) can be provided above the one formed by the perforation (2).

What I claim to be new is the following:

1. A hair comb comprising a casing having side walls, flanges on a longitudinal edge and opposite ends of one side wall engaged with the other side wall to form a closure, a grill at the other longitudinal edges of the side walls, a comb in the casing having its teeth slidable through the grill, a slide in the casing having diagonal slots therein and pins carried by the comb extending through the slots in the slide. 5

2. A hair comb comprising a casing having side walls, flanges on a longitudinal edge and opposite ends of one side wall engaged with the other side wall to form a closure, a grill at the other longitudinal edges of the side walls, a comb in the casing having its teeth slidable through the grill, a slide in the casing having diagonal slots therein, pins carried by the comb extending through the slots in the slide and a second grill in the casing parallel and spaced inwardly of the grill at the edges of the casing to prevent tilting movement of the comb in the casing. 15

3. A hair comb comprising a casing having side walls, flanges on a longitudinal edge and opposite ends of one side wall engaged with the other side wall to form a closure, a grill at the other longitudinal edges of the side walls, a comb in the casing having its teeth slidable through the grill, a slide in the casing having diagonal slots therein, pins carried by the comb extending through the slots in the slide and a strap inclosing the flanged side and ends of the casing with the ends of the strap clinchingly engaged with ends of the end flanges. 30

4. A hair comb comprising a casing having side walls, flanges on a longitudinal edge and opposite ends of one side wall engaged with the other side wall to form a closure, a grill at the other longitudinal edges of the side walls, a comb in the casing having its teeth slidable through the grill, a slide in the casing having diagonal slots therein, pins carried by the comb extending through the slots in the slide, a second grill in the casing parallel and spaced inwardly of the grill at the edges of the casing to prevent tilting movement of the comb in the casing and a strap inclosing the flanged side and ends of the casing with the ends of the strap clinchingly engaged with ends of the end flanges. 45
